UNITED STATES PATENT OFFICE.

JOEL ANDERSON COPPRIDGE, OF RICHMOND, VIRGINIA.

COOKING-STOVE.

1,155,799.

Specification of Letters Patent.

Patented Oct. 5, 1915.

Application filed July 3, 1913. Serial No. 777,253.

To all whom it may concern:

Be it known that I, JOEL A. COPPRIDGE, a citizen of the United States, and a resident of Richmond, in the county of Henrico and State of Virginia, have made certain new and useful Improvements in Cooking-Stoves, of which the following is a specification.

My invention relates to improvements in cooking stoves and it consists in the combinations, constructions and arrangements herein described and claimed.

An object of my invention is to provide a device for cooking purposes which will make use of either solid or gaseous fuel with means for protecting the gas burners when solid fuel is used with the device.

A further object of my invention is to provide a device in which the change from a solid fuel stove to one which uses gaseous fuel may be quickly and easily made.

A further object of my invention is to provide a combined stove in which the products of combustion of the solid fuel and those of the gaseous fuel are made to take a tortuous path around ovens thereby heating the latter and economizing in the use of fuel due to the fact that a greater proportion of heat is abstracted from the products of combustion during their travel than in the ordinary stove.

Other objects and advantages will appear in the following specification and the novel features of the device will be particularly pointed out in the appended claims.

My invention is illustrated in the accompanying drawing forming part of this application in which—

Figure 1 is a perspective view of the stove, Fig. 2 is a view of a portion of one of the ovens showing the damper, Fig. 3 is a section through one of the ovens, Fig. 4 is a section along the line 4—4 of Fig. 3, Fig. 5 is a vertical section through the device along the line 5—5 of Fig. 6, and Fig. 6 is a vertical section through the device along the line 6—6 of Fig. 5.

In carrying out my invention I provide a casing 1 at one end of the device, containing a fire box or combustion chamber 2, a grate 3, and an ash pit 4. Joining the top of the combustion chamber and extending to the opposite end of the stove is the lower wall 5 of the passage 6 for the products of combustion. The top wall of the stove 7 extends

over the combustion chamber and the walls 5 and 7 are supported at one end of the stove by legs 8. At the rear of the stove is an upwardly extending frame 10 having hinged brackets 11 bearing at its top a warming closet 12.

Upper and lower ovens 13 and 14 respectively are arranged within a casing 15 which is mounted on the upper wall 7 of the stove. The walls of the casing 15 as well as the wall 5 are preferably made double with some non-conductor of heat such as asbestos packing disposed between the two wall members. The upper oven 13 is slidably supported on brackets 13^a and is movable into and out of the casing in the manner shown in Fig. 6. The lower oven 14 is slidably supported on similar brackets 14^a. The ovens are provided with hinged doors such as those shown at 13^b and 14^b.

As will be seen from Fig. 5 openings 7^x are provided in the upper wall 7 of the passage 6, these openings being situated in alignment with the space between the ovens and the casing 15. Between the ovens 13 and 14 are inwardly extending baffle plates 16 and above the oven 13 is a forwardly extending baffle plate 17. An exit flue 18 is disposed at the rear of the upper part of the casing 15. Air inlets 19 are provided in the sides of the casing 15 near the bottom thereof, these air inlets being controlled by dampers 20.

Referring now particularly to Figs. 4 and 5 it will be seen that I have provided a pair of gaseous fuel burners 21 and 22, which are directly underneath the stove openings normally covered by the lids 21^x and 22^x respectively. These burners are disposed in housings such as those shown at 21^y and 22^y, carried by the wall 5. Over each burner is disposed a plate 23 which is pivotally connected with the wall 5 and is adapted to be swung out of the way of the burner when the latter is used and to be swung over the burner to protect the latter when the solid fuel is being used. These burners are fed from a main pipe 24 extending in front of the stove and provided with branches 21^z and 22^z leading to the burners and controlled by stop keys 21^k and 22^k respectively. The end of the pipe 24 communicates with the pipe 25 which is controlled by a cock 25^x. The pipe 25 in turn communicates with a

pair of burners 26 and 27 disposed underneath the lower oven 14. These burners are provided with side openings 26^x and 27^x.

From the foregoing description of the various parts of the device the operation thereof may be readily understood.

When it is desired to use solid fuel with the stove the plates 23 are swung over the burners 21 and 22, solid stove lids like those shown at 28 are provided for the stove holes above the burners and the dampers 19 are closed. The products of combustion in the fire box 2 pass in the direction shown by the arrows in Fig. 5, thence up through the openings 7^x and around the ovens and baffle plates and thence out through the flue 18. The provision of the baffle plates 16 and 17 tends to cause the products of combustion to take a longer course and hence more of the heating power of the gases is utilized in the ovens. It will be noted that the combustion chamber 2 is provided with a water back 29 with which the pipes 30 and 31 communicate; thus hot water may be supplied in the usual way.

When the device is to be used as a gas stove the protecting plates 23 are moved back to expose the burners 21 and 22. The lids 21^x and 22^x may be removed and the cooking may be done immediately over the burners. When it is desired to use the ovens 13 and 14 the burners 26 and 27 are lighted and the dampers 19 are opened to permit the entrance of air necessary for supporting combustion. The burners 26 and 27, as stated before, are provided with openings on either side and hence when solid fuel is used with the stove these burners are not clogged up with soot and dirt as they would be if the burners had openings on their upper sides.

It will be noted that as far as the ovens are concerned the products of combustion take the same course when the device is used as a gas stove as they do when solid fuel is used. The plates 23 may be moved very quickly and thus the device may be changed immediately from a gas stove to one using solid fuel or vice versa.

I am aware that other forms of the device based upon the same general plan might be made, but I consider as my own all such modifications as fairly fall within the spirit and the scope of the invention.

I claim:

1. In a combined solid fuel and gas stove, a combustion chamber, a casing, an exit flue connected with said casing, a horizontal passage for connecting the combustion chamber with the casing, the upper wall of said chamber with the casing, the upper wall of said horizontal passage being made of conducting material and having stove openings and lids for the same, a lower wall being made of non-conducting material, and burners carried by the lower wall and arranged

to register with the openings in the upper wall, said burners being below the top of the lower non-conducting wall, thereby providing an unrestricted passage for the products of combustion.

2. In a combined solid fuel and gas stove, a combustion chamber, a casing, an exit flue connected with said casing, a horizontal passage for connecting the combustion chamber with the casing, the upper wall of said horizontal passage being made of conducting material and having stove openings and lids for the same, a lower wall being made of non-conducting material, burners carried by the lower wall and arranged to register with the openings in the upper wall, said burners being below the top of the lower non-conducting wall, thereby providing an unrestricted passage for the products of combustion, and means for protecting said burners when solid fuel is used with the stove.

3. In a combined solid fuel and gas stove, a combustion chamber, a casing, an exit flue connected with said casing, a horizontal passage for connecting the combustion chamber with the casing, the upper wall of said horizontal passage being made of conducting material and having stove openings and lids for the same, a lower wall being made of non-conducting material, burners carried by the lower wall and arranged to register with the openings in the upper wall, said burners being below the top of the lower non-conducting wall, thereby providing an unrestricted passage for the products of combustion, and means for protecting said burners when solid fuel is used with the stove, said last named means comprising plates pivoted to the inner side of the lower wall and adapted to swing over said burners.

4. In a combined solid fuel and gas stove, a combustion chamber, a casing, an exit flue connected with said casing, a horizontal passage for connecting the combustion chamber with the casing, the upper wall of said horizontal passage being made of conducting material and having stove openings and lids for the same, a lower wall being made of non-conducting material, burners carried by the lower wall and arranged to register with the openings in the upper wall, said burners being below the top of the lower non-conducting wall, thereby providing an unrestricted passage for the products of combustion, housings carried by the lower horizontal wall, a burner disposed in each housing, said burners being arranged to register with the stove openings, and a pivoted lid adapted to swing over and cover the burners and constituting a portion of said housings.

5. In a combined solid fuel and gas stove, a combustion chamber, a casing, ovens disposed within said casing and spaced from the interior walls thereof, the space between

- the walls and the ovens constituting a flue, a passage establishing communication between the combustion chamber and said flue, and gas burners disposed at the bottom of said 5 passage above the level of the combustion chamber whereby the ovens in the flue may be heated by the combustion of solid fuel or gaseous fuel.
6. In a combined solid fuel and gas stove, 10 a combustion chamber, a casing, ovens disposed within said casing and spaced from the interior walls thereof, said casing being disposed above the upper level of the combustion chamber and the space between the 15 walls and the ovens constituting a flue, a passage connecting the upper part of the combustion chamber with the lower part of said flue, a burner disposed below said pas-
- sage, a lid for protecting the burner from the products of combustion of the solid fuel, 20 the upper wall of the passage having an opening registering with said burner, and a lid for said opening.
7. In a range adapted to burn either solid or fluid fuel, the combination of a fire box, 25 a substantially horizontal flue leading from the fire box, the top of said flue being adapted to support articles to be heated and the bottom thereof being formed with a depression, and a burner situated within said depression out of the path of the products of combustion from said fire box. 30
